No. 625,128.

Patented May 16, 1899.

M. STEINERT.

PIANO ACTION.

(Application filed Oct. 3, 1898.)

(No Model.)

UNITED STATES PATENT OFFICE.

MORRIS STEINERT, OF NEW HAVEN, CONNECTICUT.

PIANO-ACTION.

SPECIFICATION forming part of Letters Patent No. 625,128, dated May 16, 1899.

Application filed October 3, 1898. Serial No. 692,521. (No model.)

To all whom it may concern:

Be it known that I, MORRIS STEINERT, of New Haven, in the county of New Haven and State of Connecticut, have invented a new Improvement in Piano-Actions; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a piano-action constructed in accordance with my invention; Fig. 2, a detached broken plan view thereof.

My invention relates to an improvement in actions for grand and square pianos, the object being to confer upon the pianoforte some of those rare qualities sacrificed with the abandonment of the clavichord and to enable performers of moderate skill to produce in perfection with the pianoforte those effects (particularly those of minute dynamic variation) hitherto only within the reach of virtuosi of the highest rank, who are able to secure them by a training of the muscles of the hands and arms carried so far as to make the same in a sense supplemental to the instrument rather than mere *média* of performance.

With these ends in view my invention consists in a piano-action having certain details of construction and combinations of parts, as will be hereinafter described, and particularly recited in the claims.

In carrying out my invention as herein shown the key A is provided in the usual manner with a fly B, secured in place at its rear end by a screw B' and made vertically adjustable by a screw B² passing through its forward end. In this fly I mount a jack C, which may be arranged perpendicularly or slightly inclined forward or back, as may be found desirable in adjusting the action. At its lower end the jack is provided with an arm c', which coacts with a regulating-screw D, mounted in the horizontal portion of a flange E, extending forward from the lower edge of the hammer-lever rail E'. A regulating-screw F, horizontally mounted in the jack itself, coacts with the vertical portion of the flange E before mentioned. A regulating-screw G, coacting with the outer face

of the jack, near its upper end, is mounted in a horizontally-arranged regulating-screw rail G'. The extreme upper end of the jack 55 coacts with an oblique operating-face H, which constitutes the lower face of the forward end of a balanced hammer-lever H', which is horizontally arranged and mounted in a butt H², secured to the upper end of the 60 hammer-lever rail E' before mentioned. A hook I, mounted in the upper end of the jack, extends over the upper face of the forward end of the balanced hammer-lever H' and, so to speak, "articulates" the jack with the balanced hammer-lever and insures the restoration of the hammer-lever to its normal position with the descent of the jack. This hook 65 coacts directly with a strip J of felt or equivalent material, the operating-face H being also 70 furnished with a strip of felt or equivalent material J'. At its rear end the hammer-lever is furnished with a balancing extension H³, in which I by preference locate one or more disk-like weights H⁴, of lead. The upper 75 rear corner of the said balanced lever H' is cut away on each side to produce a tongue H⁵, in which I form a horizontal slot H⁶, which is lined with a strip of felt or leather h. The said slot receives a horizontal pin K, mounted 80 in the arms of a yoke K', formed at the rear end of the hammer-body K², which is pivotally mounted in a butt L, secured to the horizontal hammer-rail M. A slit H⁷, forming a continuation of the slot H⁶, extends into the 85 body of the hammer-lever and permits the slot to be constricted or enlarged by means of a screw H⁸. A hammer-arm N, rigidly secured in the rear end of the hammer-body K², carries the hammer-head N', which is furnished in the usual manner with a heavy 90 cushion N², of felt. The tail N³ of the hammer-head coacts with a back-check O, carried by an inclined wire O', mounted in the extreme rear end of the key A. When the 95 hammer is at rest, the hammer-arm N is supported upon the hammer-rest rail P.

It will be seen from the foregoing description that my improved action is composed not only of few parts, but that those parts 100 are simple in themselves and simply related in a continuous chain of articulated parts between the hammer and the key.

In the pianoforte as ordinarily constructed

the jack coacts directly with the hammer, which under the impulse communicated to the jack by the key causes the hammer to leap freely into the air and deliver a sharp blow upon the string, after which the hammer falls back without restraint to its depressed position. Under the ordinary construction, therefore, no note can be produced unless the key is depressed with sufficient 5 shock to effect the leaping of the key into the air with enough impulse to strike the string a blow, for the principle of construction on which the ordinary piano-action is based does not permit the hammer to strike the string 10 as the result of a soft even downward pressure upon the key, but requires a blow—not necessarily a hard blow, but at the least a blow of sufficient force to produce the shock required to cause the key to leap free into the 15 air and strike the string. Pressure, mere pressure, will not achieve this result, and cannot answer the purpose. Players of great skill and refinement—virtuosi—and also others who may have a natural touch produce 20 these necessary blows with such minute dynamic variations—with such perfect gaging of the blow to the force with which the hammer must strike the string—that the objectionable features of the ordinary piano as 25 an instrument of percussion are for the time being veiled. With the average performer, however, there is a constant failure to proportion the force of the blow upon the key to the exact volume and kind of tone required, 30 so that the player fails to reproduce his own personal and sympathetic interpretation of the score before him. Either the strings are struck too hard or, owing to the fear of striking too 35 much of a blow and producing too loud a tone, not at all. The action of the ordinary piano as ordinarily played is therefore distinguished by a series of blows more or less sharp of the hammers upon the strings and is a hard and mechanical action, the 40 harshness of which can only be overcome by the trained and sensitive touch of a virtuoso. In my improved piano-action, however, I employ a hammer-lever which is interposed between the hammer and the jack and which 45 is articulated loosely, but positively, with the hammer, on the one hand, and with the jack, on the other. Then no matter how softly the key is struck the hammer never fails to strike the string, and even a steady and uniform 50 pressure upon the key will necessarily cause the hammer to lift and strike the string. Nor after the hammer has struck the string does it drop back into its normal position; but so long as the key is depressed it holds a 55 position slightly below the string, to which it may from that elevated position be raised for repeating the stroke by depressing the key farther, the jack at this time working upon the rear end of the obtuse-angled operating-face upon the lower face of the forward end of the hammer-lever. Inasmuch as under 60 my action the hammer is not sent flying into

the air by the depression of its key, the performer maintains over the instrument a much more perfect control than he can command 70 over an instrument of the ordinary type, and for the same reason he is enabled to establish between himself and the instrument a rapport before unknown. At the same time my improved action enables the performer to produce a forte as powerful as that of an ordinary piano and with more purity of tone, while he may also produce pianissimo, crescendo, and diminuendo effects impossible on the common instrument. Furthermore, his 80 control of the hammer is so perfect that he may produce a beautiful singing legato without effort and without training. As to staccato passages they may also be produced with crispness, clearness, and brilliancy. 85

Although my improved action is well adapted, as above stated, for forte and piano playing and for the execution of the most brilliant scherzo passages, it is particularly suited for playing accompaniments and melodies 90 and all work requiring softness of tone without loss of purity or roundness. It permits an unskilled performer to produce a cantabile, which on the ordinary instrument would be far beyond his powers.

Of course if a key is released immediately after it has been depressed the ensuing descent of the jack allows the hammer to at once return to its normal position of rest on the hammer-rest rail; but if the key is not 100 at once released after having been depressed the jack will be held up under the rear portion of the oblique operating-face H of the hammer-lever, whereby the hammer will be held up in a position close to the string, which 105 it may be again, though less powerfully, caused to strike by a short "pulsion," so to speak, of the key while the same is still in its partially or even nearly depressed position. In other words, the hammer is not released directly 110 after it has struck the string, as with an ordinary piano-action, but only when the key has been allowed to return to its normally-elevated position.

Of course in carrying out my invention 115 some changes in the construction herein shown and described may be made, and I would therefore have it understood that I do not limit myself to the exact form set forth, but hold myself at liberty to make such 120 changes and alterations as fairly fall within the spirit and scope of my invention.

Having fully described my invention, what I claim as new, and desire to secure by Letters Patent, is—

1. In a piano-action, the combination with a key, of a jack mounted thereupon, a horizontally-arranged hammer-lever provided at its forward end with an oblique operating-face with which the jack coacts, a hammer-body, and means for positively articulating the upper end of the jack with the forward end of the hammer-lever, and the rear end of the hammer-lever with the hammer-body.

2. In a piano-action, the combination with a key thereof, of a jack mounted upon the said key, a horizontally-arranged hammer-lever having its forward end provided with an oblique operating-face with which the jack coacts, and its rear end furnished with a balancing extension, a hammer-body, and means for positively articulating the said hammer-body with the rear end of the hammer-lever, and for positively articulating the forward end of the hammer-lever with the upper end of the jack which supports the hammer in position near its string after the hammer has struck the same, and until the key is released and allowed to return to its normal position.
- 15 3. In a piano-action, the combination with a hammer-lever formed with a tongue having a slot from which a slit extends to permit the slot to be constricted or enlarged by means of an adjusting-screw, of a hammer having 20 a hammer-body formed with a yoke to receive the tongue, and provided with a pin passing into said slot in which it moves back and forth so as to loosely but positively articulate the hammer and lever. 25

In testimony whereof I have signed this specification in the presence of two subscribing witnesses.

MORRIS STEINERT.
